FRANCIS A. GUDGER, OF NEW YORK, N. Y., ASSIGNOR TO ARLINGTON COMPANY, OF NEW YORK, N. Y., A CORPORATION OF NEW JERSEY.

PYROXYLIN COLLAR.

No. 905,068.

Specification of Letters Patent.

Patented Nov. 24, 1908.

Application filed June 2, 1908. Serial No. 436,306.

To all whom it may concern:

Be it known that I, FRANCIS A. GUDGER, of the borough of Manhattan, in the city and State of New York, (whose post-office address is 725 Broadway, New York city,) have invented a new and useful Improvement in Pyroxylin Collars, of which the following is a specification, reference being had to the accompanying drawing, which is a 10 perspective view, partly broken away, of one form of collar embodying my invention.

In the manufacture of pyroxylin collars it is desirable to impart to the collar a rough finish so as to simulate the appearance of 15 linen, but a difficulty has been found in the use of such collars due to the fact that a rough surface on the interior of the collar makes it difficult to adjust the necktie, for the tie will not slip freely between the adjacent rough surfaces.

My invention consists in overcoming this difficulty by making a collar having a rough exterior finish as indicated at 2 and imparting to it on the interior surface a polished 25 finish as indicated at 3, and I find that in this way the tie can be readily adjusted in the collar, and a more useful and efficient 30 collar, having all the advantages in appearance of the ordinary linen-finished collar can be produced.

The rough finish of the pyroxylin collar is ordinarily imparted by pressing the collar either in a mold or while the pyroxylin is in sheet form, between linen cloths, but I have 35 found that it is not desirable to attempt to impart the polished finish at the same operation as that in which the rough finish is given, for to place a polished and rough surface at once on opposite sides of the collar

or sheet requires a heavier pressure to produce the polished surface than is needed to produce the rough surface, and therefore exaggerates the roughness of the collar and produces undesirable effects. It is therefore preferable to impart the polished surface to 45 the collar at a separate operation. Where the rough surface is given to the pyroxylin in sheet form I take the sheet, either before or after it has been pressed to give the rough surface, and polish the sheet on one side 50 with a buffering wheel or subject it to heat and pressure against a polished plate.

Where the collar is to be molded with a rough surface, I take the collar-blank after it is finished in the mold and polish it on the 55 inner surface with a buffering wheel.

Collars produced as above described would have tabs with smooth surfaces which being exposed to view would be undesirable. I prefer to obviate this difficulty by roughening the surface of the tabs as indicated at 4, which I may do by stamping them with a linen stamp or by finishing them with a rough wheel, that is, a wheel to which ash or pumice is applied.

I claim as my invention.

1. A composition collar having a roughened exterior surface and a polished interior surface.

2. A composition collar having a rough outer surface, a polished inner surface and tabs with roughened surfaces.

In testimony whereof, I have hereunto set my hand.

FRANCIS A. GUDGER.
